Baldwin Yale ATTORNEY.

UNITED STATES PATENT OFFICE.

OTTO A. KNOOPP, OF OAKLAND, CALIFORNIA.

COMPRESSION-RHEOSTAT.

1,345,015.

Specification of Letters Patent. Patented June 29, 1920.

Application filed October 16, 1916. Serial No. 125,862.

To all whom it may concern:

Be it known that I, Otto A. KNOOPP, a citizen of the United States, residing at the city of Oakland, county of Alameda, and State 5 of California, have made a new and useful invention—to wit, Improvements in Compression-Rheostats; and I hereby declare the following to be a full, clear, concise, and exact description of the same.

10 Among the objects of this invention are to provide a rheostat having a wide range of applications, great fineness of regulation, and large heat dissipating capacity.

In this specification and the annexed 15 drawings, the invention is illustrated in the form considered to be the best but it is to be understood that the invention is not limited to such form, because it may be embodied in other forms, and it is also to be understood 20 that in and by the claims following the description, it is desired to cover the invention in whatever form it may be embodied.

So far as I am aware, I am the first to 25 surround or submerge a compression rheostat in oil or other non-electrolytic liquid. Such submersion results in greater uniformity in the action of the compression pile, higher efficiency, greater durability, more 30 rapid dissipation of heat therefrom and superior electrical and mechanical advantages. The film of oil between each of the contacting conductors forming the pile, prevents arcing and sparking therebetween, insures 35 the positive and uniform separation between each and all of the conductors under variations of mechanical pressure on the pile; whereas a pile of dry disks or conductors do not separate uniformly and are apt to stick 40 together in groups and separate proportionately too far apart at other points, setting up arcing and sparking that breaks down the opposing surfaces of the disks, destroying their usefulness and interfering with the uniform resistance of the pile as a whole, 45 setting up excessive resistance at points with a resultant concentration of heat, whereas the resistance should be uniform throughout the pile. The oil is also particularly valuable as a dissipating agent for conducting 50 heat away from the pile.

In the accompanying one sheet of drawings:

Figure 1 is a front elevation partly in 55 cross section, illustrating a simple form of the invention arranged for manual control of the compression of the rheostat pile.

Fig. 2 is a diagrammatic front elevation in cross section of a magnetically controlled compression rheostat constructed in accordance with this invention.

In detail the construction illustrated in the drawings includes, Fig. 1, the inclosing tubular casing 1 preferably of metal, lined with the insulation 2. The top and bottom plugs 3 and 4 of conducting metal are threaded into the insulation 2 at the opposite ends forming a hermetically sealed chamber with the outer casing 1. The compression rheostat 5 is composed of disks of carbon, graphite, or other suitable material in superimposed arrangement as illustrated; the pile resting upon the lower plug 4. A piston composed of the circular heads 6 and 7 spaced apart by the rod 8, is interposed between the pile 5 and the plug 3. This piston is of electro-conductive material. The adjusting screw 9 is threaded in the plug 3 and has the insulating knob 10, by means of which the screw may be turned. The lower end of the screw 9 is pivoted in the piston 7, whereby the pressure on the resistance pile 5 may be regulated by advancing or retracting the screw 9. The coil spring 11 expanding between the head 7 and the annular ring 12 is provided to take up lost motion in the threaded engagement between the screw 9 and the plug 3, to permit a finer and more positive adjustment of the pressure on the rheostat pile. The annular ring 12 upon which the spring 11 bears, is supported by the screws 13—13 projecting through the walls 1 and 2 into which they are threaded. The casing is hermetically sealed by the gasket 14 at the bottom and by the gasket 15 at the top forced under compression by the cap 16 screwed onto the casing 1.

The current passing through the pile passes into the device through the terminal 17, held in contact with the plug 3 by the binding nut 18 threaded thereon; passes through the screw 9; through the piston; through the resistance pile 5, and passes out the terminal 19 fixed in the plug 4 by the binding screw 20.

Before screwing in the plug 3 and sealing the casing the latter is filled with oil or other suitable liquid to entirely submerge the pile 5. Practice has proven that the film of liquid between the different disks forming the compression rheostat unit 5, does not to 110 any practicable extent increase the resistance of this unit. It has been further observed

that the fineness of regulation of the rheostat has been materially improved by the introduction of the oil, as the liquid increases the adhesive power of the disks and prevents the parting of the rheostat or pile at any one point when the pressure becomes low, which prevents arcing between the different disk units, which arcing on a dry compression rheostat usually destroys rapidly the good regulating qualities of the rheostat.

The invention operates substantially as follows: The resistance to the current passing through the pile 5 varies with the pressure applied thereto. Resistance to the current passing through the instrument is regulated by screwing down or backing off the knob 10; the resistance is less when the pile 5 is compressed so that all the disks make good contact with each other; inversely, the resistance increases as the pressure is released and the several disks forming the pile are separated by the film of oil. The current passing through the pile 5 generates heat, which is transmitted through the oil 21 which dissipates it by natural radiation from the metallic shell 1, with which the oil makes contact through the openings 22 in the insulation 2. The interposition of the spring 11 insures a uniform application and release of pressure by taking up the lost motion in the screw thread of the screw 9.

Fig. 2 illustrates diagrammatically a form of compression rheostat that may be operated from a remote control by applying the pressure to the pile magnetically. The construction includes the oil tight inclosing casing 23, having an iron clad solenoid 24 submerged therein, suitably wound as at 25 to create a magnetic field when the terminals 26-26 are connected in circuit. The compression rheostat 27 is similar in construction to the rheostat pipe 5 and is connected in circuit to the terminals 28-28. When the coil 25 is excited the magnetic field created sucks in the core 29, the rise of which compresses the interposed spring 30 and applies pressure to the compression pile 27. The stem 31 of the core has a tapered base 32, which acts as a valve for closing the opening 33 of the inclosing casing 24 of the solenoid. When the core 29 rises it displaces the oil confined in the space 34 which escapes through the gradually restricted opening 33 giving a dash pot effect compelling a graduated uplifting of the core 29 and the consequently graduated application of pressure

to the pile 27, the oil contained within the casing 23 serving the double purpose of serving as a dash pot liquid in addition to the other functions previously described with respect to the compression pile. Immersion is equally effective irrespective of the particular form of the conductors, such as disks, rods, tubes and the like.

The two embodiments of this invention illustrated diagrammatically in the drawings will serve to suggest modifications within the purview of said invention to meet special requirements.

Having thus described this invention, what I claim and desire to secure by Letters Patent is:

1. A rheostat including an inclosing casing containing a liquid; a compression rheostat immersed in said liquid; a solenoid immersed in said liquid and having a core adapted to compress said compression rheostat; and a dash pot between said core and the top of said solenoid.

2. A rheostat including an inclosing casing containing a liquid; a compression rheostat immersed in said liquid; a solenoid having an opening with a restricted outlet; a core in said opening having a tapered extension through said restricted opening and bearing against said rheostat.

3. A rheostat including an inclosing casing containing a liquid; a compression rheostat immersed in said liquid; a solenoid immersed in said liquid and having a core adapted to compress said compression rheostat.

4. A rheostat including an inclosing casing containing a liquid; a compression rheostat immersed in said liquid; a solenoid immersed in said liquid; a core within said solenoid and adjustably connected to said rheostat.

5. A rheostat including an inclosing casing containing a liquid, a compression rheostat comprising a series of disks immersed in said liquid; a plunger in alignment with said rheostat; a spring interposed between said plunger and rheostat and means contiguous to said plunger for regulating the tension on the rheostat disks.

In testimony whereof I have hereunto set my hand at San Francisco, California, this 26th day of September, 1916.

OTTO A. KNOPP.

In presence of—

BALDWIN VALE,
A. J. HENRY.
